UNITED STATES PATENT OFFICE.

CLARENCE D. TRUSSELL, OF NEW YORK, N. Y., ASSIGNOR TO TRUSSELL MANUFACTURING COMPANY, OF NEW YORK, N. Y., A CORPORATION OF NEW YORK.

TEMPORARY BINDER.

No. 880,053.

Specification of Letters Patent.

Patented Feb. 25, 1908.

Application filed June 15, 1907. Serial No. 379,106.

To all whom it may concern:

Be it known that I, CLARENCE D. TRUSSELL, a citizen of the United States, residing at the borough of Brooklyn, New York city, 5-in the county of Kings and State of New York, have invented certain new and useful Improvements in Temporary Binders, of which the following is a specification.

My invention relates to temporary binders 10 of the type shown in my application Serial Number 306,541, filed March 17, 1906.

The object of my invention is to provide a binder of simple and cheap construction which may be readily operated for the 15 insertion or withdrawal of sheets.

Figure 1 of the drawings is a perspective view of the temporary binder in open position. Fig. 2 is a side view of a pair of the sheet-holding prongs in closed position, the 20 parts below being shown in section. Fig. 3 is a similar view showing the prongs open for the withdrawal of sheets. Fig. 4 is a similar view showing the sheet-holding prongs and covers closed. Fig. 5 is a side view of a pair 25 of sheet-holding prongs. Fig. 6 is a plan view of the spring plate. Fig. 7 is a rear view of the same showing the binding plate.

Referring to the drawings, 1 is a spring plate adapted to be secured to the back 2 30 and covers by means of the binding plate 3 whose end projections 4 are bent upward and inward through the notches 5 in the ends of spring plate 1 to clamp together said spring plate 1 and the binding plate 3 so as to hold 35 securely between said plates the binding strip 6 which extends on either side of the metal spring plate 1 between the outer layer 7 of the covers and a stiffening board 8 whose inner end is adjacent to and parallel with the 40 side of spring plate 1. Each cover has a finishing layer 9 overlying the stiffening board 8. The spring plate 1 is composed of a curved base portion 10, from which are bent inwardly two parallel wings 11 which 45 are provided with oppositely arranged notches 12. The sheet-holding prongs 13 are made in two pieces, one piece having at its lower end a tongue 14 adapted to engage a groove or notch 15 in the lower end of the 50 opposite prong. The lower face of groove 15 is prolonged into the tongue 16, which is adapted to contact with the lower face of the opposite prong to stop the opening movement of the prongs, as best illustrated in Fig. 55 3. Each prong has a notch 17 on its lower

edge adapted to be engaged by the inner edge 18 and one of the notches 12 in spring plate 1. The upper sides of notches 17 are cut away at an angle so that they will not contact with the wings 11 when the prongs 60 are in the open position, as best illustrated by Fig. 3.

Adjacent to each cover is a flyleaf 19 composed of a metallic plate 20, around which is pasted a sheet 21 of glazed paper or similar 65 material so as to completely envelop the same and extend outward beyond said plate, as best illustrated in Fig. 1. Each flyleaf 19 is apertured along its inner edge for the reception of the prongs 13. At each of the 70 apertures 22 the metal plates 20 are bossed or bent inwardly as indicated in Fig. 1, and best shown in Figs. 2, 3 and 4. The sheets adapted to be held in the binder are indicated at 23. Such sheets are, of course, apertured 75 for the reception of the prongs 13, as indicated in Figs. 3 and 4.

The operating parts consist of the spring plate 1 and the several pairs of sheet-holding prongs 13. The flyleaves 19 operate to open 80 the prongs as hereinafter explained.

The several layers of the covers should be pasted firmly together for the sake of neatness and to fasten securely the binding strip 6 by means of which the parts are held together. 85

The spring plate 1 is made of resilient metal. When the sheet-holding prongs are in the closed position illustrated in Fig. 2, the joint formed by the tongue 14 and groove 15 90 is slightly below the level of the edges 18 which engage the notches 17 so that the spring pressure of the spring plate 1 holds the sheet-holding prongs 13 in closed position. The prongs 13 may be opened by pulling each 95 pair apart separately by the fingers. As the prongs open they rock slightly on edges 18 as a center so that their lower ends are raised, carrying the joint between the tongue 14 and groove 15 above the level of edges 18 so that 100 the pressure of the spring plate 1 then serves to force the prongs apart and into the position shown in Fig. 3. The opening movement of the prongs is terminated by the impact of tongue 16 against the lower edge of 105 the opposite prong. To close the prongs they are moved together by the fingers. This movement lowers the joint of the prongs below the level of edges 18 so that 110 spring plate 1, at the moment the joint

passes the central position, serves to snap the prongs 13 together and retain them in the position shown in Figs. 1, 2 and 4. The sides of notches 12 serve to hold the prongs 13 from movement sidewise and in exact alignment.

A more convenient method of opening the prongs to insert or release a number of sheets is illustrated in Fig. 3. The sheets are 10 parted at the selected points and turned back with the fly-leaves and covers. A slight pressure on the sheets at about the outer edge of each metallic plate 20 will cause the several pairs of prongs 13 to open simultaneously. In using this method of opening the prongs, the metallic plates 20 act as levers. The metallic plates 20 should be stiff enough so that the opening movement will be communicated to all of the prongs by pressure at 20 only one point. The inward bossing or bending of the plates 20 raises the edges of the apertures 22 so that they will not catch in notches 17 in prongs 13. The bossing or bending at the apertures 22 also permits the 25 flyleaves to nest around the prongs 13 when the binder is closed, as best illustrated in Fig. 4.

In addition to serving as a means for opening the prongs, the flyleaves 19, with their 30 metallic plates 20, serve to guide and protect the paper sheets 23 when the covers are being opened or closed.

What I claim as new and desire to secure by Letters Patent is:

- 35 1. In a temporary binder, a pair of metallic plates apertured for the mating prongs and bossed or bent inwardly at the outer and inner edges of each aperture.
2. In a temporary binder, a pair of metal-

lic plates apertured for the mating prongs 40 and bossed or bent inwardly between each aperture and the inner edge of the plate to form a groove in which a prong will lie when the binder is closed.

3. In a temporary binder, a spring plate, a 45 series of mating prongs, and a pair of flat, metallic plates apertured for the mating prongs and bossed or bent inwardly at the outer edge of each aperture so that the plates will not catch in the joints between the 50 spring plate and the mating prongs.

4. In a temporary binder, mating prongs; means to retain said prongs in open or closed position; and apertured metallic plates engaged by said prongs and adapted to open 55 the prongs when pressed backward by the operator.

5. In a temporary binder, mating prongs; covers; and a fly-leaf next to each cover engaging the mating prongs and composed of a 60 metallic plate at its base covered by paper and having a paper wing or extension outwardly.

6. In a temporary binder, mating prongs jointed together, means to retain said prongs 65 in open or closed position, a tongue 16 projecting sidewise from one prong below the joint between said prongs and adapted to contact with the flat lower surface in the opposite prong to stop the opening movement 70 of the prongs.

Signed at New York city in the county of New York and State of New York this 13th day of June A. D., 1907.

CLARENCE D. TRUSSELL.
